UNITED STATES PATENT OFFICE.

HERBERT M. LOURIE, OF KEOKUK, IOWA, ASSIGNOR TO LAURA A. LOURIE,
OF SAME PLACE, AND HARVEY E. ELLINGTON.

DESIGN FOR A CREAM-SEPARATOR.

SPECIFICATION forming part of Design No. 35,185, dated October 15, 1901.

Application filed July 10, 1901. Serial No. 67,795. Term of patent 7 years.

To all whom it may concern:

Be it known that I, HERBERT M. LOURIE, a citizen of the United States, residing at Keokuk, in the county of Lee and State of Iowa, have invented and produced a new Design for Cream-Separators, of which the following is a full, clear, concise, and exact description, reference being had to the accompanying drawings, forming a part of this specification.

10 I have illustrated my design in the accompanying drawings, in which—

Figure 1 is a view of the design looking at the same from above. Fig. 2 is a longitudinal sectional view thereof.

15 As shown in the drawings, the cream-separator which embodies my novel design comprises an exterior oblong reservoir or casing *a* and an interior oblong reservoir *b*, which is of greater length than width and which 20 rests at one end in contact with the end of the exterior reservoir *a*. The bottom *b*² of the inner reservoir *b* slants toward the front

end and is substantially V shape in cross-section. At the rear end of the reservoir *b* is a downwardly-extending leg *b*'. At the forward end of the structure is a window *c*.

25 The essential feature of the design is the provision of the outer and inner oblong reservoirs, the said inner reservoir having a bottom slanting toward the front and a leg at 30 the rear end thereof, substantially as shown and described.

Having described my design, what I claim as new, and desire to secure by Letters Patent, is—

35 The design for a cream-separator, substantially as shown and described.

In witness whereof I have hereunto subscribed my name in the presence of two witnesses.

HERBERT M. LOURIE.
